UNITED STATES PATENT OFFICE.

SYDNEY BURT GARDNER, OF BENSON, MINNESOTA.

TRENCH-WALL SUPPORTER.

Application filed February 5, 1925. Serial No. 7,121.

To all whom it may concern:

Be it known that I, SYDNEY BURT GARDNER, a citizen of the United States of America, residing at Benson, in the county of Swift and State of Minnesota, have invented certain new and useful Improvements in Trench-Wall Supporters, of which the following is a specification.

This invention relates to trench wall supporting machines of the general type shown in my prior Patent No. 1,391,624, granted September 20, 1921, entitled "Trench wall supporting machine", and has for one of its objects to improve the construction of the apparatus shown and described in the said patent.

The said prior machine comprises a pair of laterally expandable sections which are adapted to support sheet piling against the walls of a trench, the said sections being movable relative to one another in both vertical and horizontal directions whereby the machine may be advanced as the work progresses, so that the piling at the rear of the machine may be removed and placed in front thereof. Manually operated means are provided for producing the relative movements of the two sections in the vertical and horizontal directions and also for producing the lateral expansion of the sections, to cause them to engage the piling at the sides of the trench.

The present invention, on the other hand aims to produce an apparatus of the character described in which the lateral expansion, as well as the relative horizontal and vertical movements of the sections are accomplished through the medium of power devices, in the present instance shown as comprising fluid pressure cylinders suitably disposed and connected to the various parts to produce the desired movements.

A further object of the invention is to provide an apparatus of the class described having a plurality of transverse expansion cylinders with pistons therein, and a cylinder having a piston for producing the horizontal longitudinal movements of the sections, the movements of all of which pistons are controlled by a single valve.

A still further object of the invention is

to provide a simple and effective means for controlling the pistons which accomplish the vertical movements of the sections.

A still further object of the invention is to produce a device of the class described which will be simple in construction, comparatively inexpensive to manufacture and more efficient in use than those heretofore proposed.

With the above and other objects in view, which will appear as the description proceeds, the invention consists in the novel details of construction and combinations and arrangements of parts more fully hereinafter described and particularly pointed out in the appended claims.

Referring to the accompanying drawings, forming a part of this specification, in which like reference characters designate like parts in all the views:

Figure 1 is a side elevational view of a trench wall supporting machine constructed in accordance with the present invention, the nearest pile supporting rails being omitted;

Figure 2 is a transverse sectional elevational view of a portion of one of the sections showing one of the transverse expansion cylinders and its associated parts;

Figure 3 is a horizontal sectional view, partly in elevation, of the parts shown in Fig. 2, taken approximately on the plane indicated by the line 3—3 of the said figure, looking down.

Figure 4 is an end elevational view of the parts shown in Figure 3, with one of the pile supporting rails omitted.

Figure 5 is an elevational view partly in section of one of the vertical or raising cylinders and its associated parts.

Figure 6 is a sectional view on an enlarged scale of a portion of the parts shown in Figure 5 taken approximately on the line 6—6 of the said figure, looking down.

Figure 7 is a detail cross sectional view taken approximately on the plane indicated by the line 7—7 of Fig. 6, looking in the direction of the arrows.

Figure 8 is a vertical sectional view through the cylinder shown in Figure 5 taken at right angles to said figure.

Figure 9 is an enlarged detail view of a

portion of the locking parts shown in Figure 8.

Figure 10 is an enlarged detail perspective view of one of the locking elements 5 shown in Figures 8 and 9.

Figure 11 is a top plan view partly in section, of the cylinder for producing relative longitudinal movements of the sections.

Figure 12 is a transverse sectional view 10 taken approximately on the plane indicated by the line 12-12 of Fig. 11.

Figure 13 is a side elevational view of one end of one of the pile supporting rails.

Figure 14 is a top plan view of the parts 15 shown in Figure 13.

Figure 15 is an enlarged cross sectional view taken approximately on the plane indicated by the line 15-15 of Fig. 13.

Figure 16 is an end elevational view of 20 the valve for controlling the lateral expansion cylinders.

Figure 17 is a top plan view of the same.

Figure 18 is a longitudinal sectional view of the said valve.

25 Figure 19 is an enlarged cross sectional view of the said valve taken approximately on the plane indicated by the line 19-19 of Figure 18.

Figure 20 is a similar view taken on the 30 line 20-20 of Figure 18.

Figure 21 is a diagrammatic development of the valve casing.

Figure 22 is a similar view of the valve 35 plug.

Figures 23 and 24 are detail cross sectional views of a four-way valve employed for controlling the vertical or lifting cylinders and

40 Figure 25 is a longitudinal sectional view of this last mentioned valve.

As in the construction shown in the said prior Patent No. 1,391,624, the present machine comprises two sections A and B, composed respectively of the pairs of upright members A' and B' to which are secured the horizontal rail members a and b. These said sections, while interconnected, are so constructed as to be movable relative to one another whereby they may be advanced in a horizontal direction, step by step, and also if necessary, in a vertical direction. As was the case in the said prior patent, the horizontal rails a and b are so supported upon their respective sections A and B, that they are capable of lateral movement, whereby they may be caused to engage the sheet piling when they are moved laterally outwardly to support the same and to disengage the said piling when they are collapsed or moved inwardly to permit the piling to be removed from the rear of the machine and advanced to the front as the work progresses.

65 In order to accomplish this lateral movement, in the present instance, the section A

is provided with a plurality of horizontally disposed cylinders 30 suitably supported upon the upright members A', each of which carries a pair of pistons 31 and 32 (see Figure 3) respectively, provided with piston rods 33 and 34, which are connected at their outer ends by suitable non-rigid connections 35 to the horizontal side rails a. By providing several sets of members 35 in different lengths, which may be substituted 70 one for the other, the relative transverse positions of the rails A and B may be varied to accommodate the apparatus to trenches of different widths. The said cylinders 30 are provided intermediate their ends with 75 suitable ports 36, through which air or other fluid under pressure may be introduced from a supply pipe 37 into the said cylinders between the adjacent face of the pistons 31 and 32 as will be readily understood 80 from Figure 3. It thus results that when air or other fluid pressure is so admitted between the pistons 31 and 32, that the said pistons will be forced in opposite directions and will through their piston rods 33 and 34 and the connections 35, force the horizontal rails, such as a, outwardly in a horizontal lateral direction, whereby they may be caused to engage sheet piling which has been positioned within the trench adjacent 85 the walls thereof. The said rails may be moved at the opposite direction upon the release of fluid pressure in the cylinders 30 by suitable springs 38 (see Fig. 2), or in 90 any other suitable manner.

100 In order that the rails such as a may be positively maintained in their outward positions, against the possibility of a failure to constantly maintain fluid pressure within the cylinders, I have provided an automatic locking mechanism which will securely retain the pistons and rails in their outward positions after they have been forced to such positions by the fluid pressure. One form 105 of such locking mechanism is illustrated in Fig. 3, wherein the piston rods, such as 34 are illustrated as being provided with a plurality of teeth or serrations 40 which are adapted to be engaged by companion teeth or serrations 41, provided on the end of a reciprocable dog or slide member 42, which is slidably mounted in an extension 43 of the cylinder head 44. The outer end of the said dog 42 is provided with a notch or recess 45 which receives the end 46 of a lever 47 pivoted as at 48 in ears 49 with which the cylinder head is provided. The other end 50 of the said lever 47 projects through a slot 51 provided in a cylinder or housing 52, which is mounted on the main cylinder 30 and the said lever end engages in a notch 53 formed in a locking piston 54 which is mounted in the said locking cylinder 52. Fluid pressure may be supplied to said cylinder 52 upon the piston 54, through a pipe 110

55, and a coiled spring 56 is interposed between the bottom of the piston 54 and the wall of the cylinder 30 to normally urge the locking piston 54 upwardly to locking position.

It will be clear from the construction just described that when fluid pressure is admitted into the cylinder 52 from the pipe or conduit 55, that it will force the piston 54 downwardly against the pressure of the spring 56 and in so doing, it will produce a rocking movement of the levers 47 about their pivots 48, whereby the ends 46 of the said levers will be caused to slide the dogs 42 outwardly to disengage their ratchet teeth or serrations 41 from the companion teeth of the pinion rods 33 and 34. When this movement has been accomplished, the piston rods may be freely moved in either direction to collapse the horizontal rails *a* to release the piling with which the said rails have been in contact.

The transverse expansion cylinders have been described in detail in connection with the section A, but, it will be understood that the section B is likewise provided with similar cylinders 57 (see Figure 1) for governing the movements of the horizontal rails *b* of that section. It will also be understood that these cylinders 57 are provided with similar locking devices for locking the rails *b* in extended positions.

For producing the relative vertical movements between the two sections, the present invention provides a pair of vertical cylinders 60 which are rigidly secured to the vertical frame members B' of the section B. These cylinders are shown in detail in Figures 5 to 10 inclusive and are provided with suitable ports 61 and 62 through which fluid pressure may be admitted to and exhaust from the interior of the said cylinders to produce movements of the piston 63 mounted therein. The said pistons are provided with piston rods 64 which extend downwardly and carry at their lower ends sleeves 65 which are provided with serrations or teeth 66 for engagement with dogs 75, whereby the parts may be locked in desired vertical adjustment as will presently appear. The said piston rods 64 also pass through a cross head member 67, which is provided with a transverse shaft 68 which carries at its outer ends, the rollers 69 running in the channel members 70 which are rigidly connected to the section A by plates 71.

It will be noted that the sleeve member 65 is provided with two sets of serrations or teeth 66 which are inclined in opposite directions, (see Figure 10). Each of these sets of teeth is engaged by a horizontal sliding dog 75 which dogs are connected as at 76 to piston rods 77 which carry pistons 78 mounted in the small horizontal cylinders

79 (see Figures 6 and 9). Fluid pressure may be introduced into the said cylinders 79 from pipes 80, through ducts or passages 81 as will be clear from the drawings. It is thus obvious that by controlling the admission of the fluid pressure to these cylinders 79, that one or the other of the dogs 75 may be engaged and disengaged from its respective teeth 66 to permit the raising or lowering of the piston rod 64 and its piston 63 75 within the cylinder 60 in response to the admission of fluid pressure therein.

In order to accomplish the longitudinal horizontal relative movements between the sections A and B, I have provided on the channel irons 70, a horizontal cylinder 85 provided with a piston 86 having a piston rod 87, the free end of which 88 is received in the cross head member 67 (see Figures 8 and 11) and is rigidly secured thereto. 85 Fluid pressure may be admitted to either end of this cylinder from suitable pipes or other connections (not shown), through the ports 89 and 90. It will be understood that in accomplishing these relative movements 90 of the sections when section A is free i. e., its rails are drawn in, the vertical members A' thereof which are rigid with the channels 70 are supported by the rollers 69 and when the section is advanced the channels 95 move on the rollers; whereas when section B is free and is advanced the rollers travel in the channels.

As above stated, it is an important feature of the present invention to provide a single valve means for controlling all of the several transverse expansion cylinders upon both sections A and B and also for controlling the operation of the piston 86 in the horizontal longitudinal moving cylinder 85 105 and one form of such valve is illustrated in detail in Figures 16 to 22 inclusive. As will be clear from the said figures, this valve comprises a casing or housing 95 which is preferably tapered substantially as shown and provided at the larger end with a hollow cap member 96 through which passes a valve spindle 97 carrying the handwheel 98 by means of which the valve may be manipulated. The casing 95 is suitably supported 115 upon the upright frame members A' of section A by means of a bracket 99 and a fluid pressure supply pipe 100 leads into a hollow cap 96 substantially as shown.

The valve casing or housing 95 is provided with a plurality of arcuately spaced hollow ribs 101, disposed around its circumference, these ribs being here shown as six in number and providing longitudinally extending passages 102, 103, 104, 105, 106, and 107. 125 The inner wall 108 of the valve casing is provided with a plurality of ports 109 affording communication between these various passages and the interior of the said casing and there is rotatably mounted within 130

the interior of the casing, a conical plug 110, which is provided with suitable ports 111 adapted to register at predetermined times with the ports 109 of the casing, the 5 said plug is provided intermediate its ends with a transverse web or partition wall 112 dividing it into two chambers 113 and 114, the former of which may be termed the admission chamber while the latter constitutes an exhaust chamber.

10 The ports 109 and 111 of the valve members are of such dimensions and so positioned that the cycle of valve operation is as follows:

15 1. Fluid pressure is admitted to all six cylinders 30 on section A to expand the rails *a* transversely.

20 2. Fluid pressure is admitted to all six safety cylinders 52 on cylinders 57 of section B to release the locks of these cylinders.

25 3. Fluid pressure is admitted to one end of longitudinal cylinder 85 to move section B forward.

30 4. Fluid pressure is admitted to all six cylinders 57 on section B to expand the rails *b*.

35 5. Fluid pressure is admitted to the six safety cylinders 52 on cylinders 30 to release the locks thereof.

40 6. Fluid pressure is admitted to the other end of the longitudinal cylinder 85 to move section A longitudinally.

45 Each movement of the valve is through an arc of 60° and one complete turn of the hand wheel 98 makes a complete move of the machine.

50 In order to control the vertical movements of the sections through the lifting cylinders 60 and their associated pistons, it is preferred to provide two four-way valves, one of which is shown in detail in Figures 40 23, 24 and 25. These valves of course may be of any suitable construction, but are here shown as comprising a casing or housing 55 115, which is preferably conical in section and which is provided with a plurality of ports 116, 117, 118, and 119.

55 A conical valve plug 120, is seated in the said housing for rotation therein by means of a suitable handle 121 and is retained in position by means of a suitable locking nut 122 as will be clear from Figure 25. The said plug is provided with suitable passageways 123, 124, 125 and 126 whereby fluid pressure may be fed to either end of the cylinders 60 at will, in order to accomplish the raising and lowering movements of the respective frames A and B.

60 It will be noted that in the present instance, the supporting rails *a* and *b* are extended somewhat further to the rear of the apparatus than was the case in my said prior patent, so that they may afford adequate support to the sheet piling which supports

65 the trench walls for a considerable distance behind the machine. It thus results that the operator who is laying the pipe in the trench is afforded additional room in which to work, since in the present instance he is working behind the machine instead of between the sections as was the case in the previous apparatus.

70 The said rails A and B may be of any suitable construction, but are here shown as comprising spaced longitudinal-metallic strips 130 which are secured together as by rivets or bolts 131 which pass through suitable spacing collars 132. The extreme ends of the rails are spaced by collars of decreasing lengths as will be readily understood from Figure 14, so that the said rails finally meet as at 133.

75 It will thus be seen that this invention provides a trench wall supporting machine of the same general character as that described and claimed in my prior patent which may be power actuated to automatically advance as the trench progresses and which may also be caused to move upwardly and downwardly to accommodate any different depths of trench. It will also be seen that the means for expanding the rails laterally as well as the means for moving the sections longitudinally are so inter-related 80 as to be controlled by a single fluid pressure valve and that a complete step or movement of the device may be accomplished by a single revolution of the valve plug. Also that the vertical power means are vertically controlled through the medium of a pair 85 of simple four-way valves.

90 It is obvious to those skilled in the art 95 may vary the details of construction as well as the arrangement of parts without departing from the spirit of the invention and therefore it is not wished to be limited to the above disclosure, except as may be required by the claims.

Claims:

1. In a trench wall supporting machine, 110 a pair of relatively movable sections; power means for moving said sections longitudinally relative to one another; power means for expanding said sections laterally toward the trench walls; and a single means 115 for controlling both of said power means.

2. In a trench wall supporting machine, 120 a pair of relatively movable sections; power means for alternately moving said sections longitudinally relative to one another; power means for alternately expanding said sections toward the trench walls; and a single means for controlling successively the actuation of said power means.

3. In a trench wall supporting machine, 125 a pair of relatively movable sections; fluid pressure means for alternately moving said sections longitudinally; additional fluid pres-

sure means for expanding said sections laterally; and a single valve for controlling both of said fluid pressure means.

4. In a trench wall supporting machine, 5 a pair of relatively movable sections; fluid pressure means for alternately moving said sections longitudinally; additional fluid pressure means for expanding said sections laterally; a single valve for controlling both 10 of said fluid pressure means; independent fluid pressure means for moving said sections vertically relative to one another; and an additional valve for controlling said last named fluid pressure means.
- 15 5. In a trench wall supporting machine, a pair of relatively movable sections; power means for expanding said sections laterally; and means for positively locking said sections against lateral movement.

- 20 6. In a trench wall supporting machine, a pair of relatively movable sections; means for expanding said sections laterally; means for locking said sections; and means operable in one direction by fluid pressure for 25 unlocking said sections from expanded condition.

7. In a trench wall supporting machine, a pair of relatively movable sections; fluid pressure means for expanding said sections laterally; means for locking said sections; fluid pressure releasable means for unlocking said sections; and a single valve for controlling both of said fluid pressure means.

- 35 8. In a trench wall supporting machine, a pair of relatively movable sections; fluid pressure means for expanding said sections laterally; means for locking said sections; fluid pressure releasable means for unlocking said sections; additional fluid pressure 40 means for moving said sections longitudinally relative to one another; and a single valve for controlling all of said fluid pressure means.

- 45 9. In a trench wall supporting machine, a pair of relatively movable sections; fluid pressure means for expanding said sections laterally; means for locking said sections; fluid pressure releasable means for unlocking said sections; additional fluid pressure 50 means for moving said sections longitudinally relative to one another; a single valve for controlling all of said fluid pressure means; the other fluid pressure means for moving said sections vertically relative to one another; and a separate valve for controlling said last named means.

- 55 10. In a trench wall supporting machine, a pair of relatively movable sections, each comprising a frame, transversely disposed 60 cylinders carried by said frames; pistons provided with piston rods, mounted in said cylinders; longitudinally extending rails carried by said piston rods; and means for applying fluid pressure to said cylinders.

- 65 11. In a trench wall supporting machine,

a pair of relatively movable sections, each comprising a frame; transversely disposed cylinders carried by said frames; a pair of pistons mounted in each cylinder, adapted to move in opposite directions under fluid 70 pressure; piston rods carried by pistons; longitudinally extending rails carried by said rods; and means for supplying fluid pressure to said cylinders.

12. In a trench wall supporting machine, 75 a frame; a transversely disposed cylinder carried by said frame; a piston in said cylinder; a piston rod rigid with said piston; means for engaging said piston rod to prevent movement thereof in one direction; and 80 means for moving said last named means into and out of engagement with said piston rod.

13. In a trench wall supporting machine, 85 a frame; a transversely disposed cylinder carried by said frame; a piston in said cylinder; a piston rod rigid with said piston; means slidable transversely of the axis of said rod for engaging the same to prevent movement thereof in one direction; means 90 for sliding said last named means into and out of engagement with said rod, and a pile engaging rail carried by said rod.

14. In a trench wall supporting machine, 95 a frame; a transversely disposed cylinder carried by said frame; a piston in said cylinder; a piston rod rigid with said piston, provided with a series of teeth; a member slidable transversely of the axis of said piston rod, adapted to engage said teeth to prevent movement of said rod; means for sliding said member into and out of engagement with said teeth; and a pile engaging rail carried by said piston rod.

15. In a trench wall supporting machine, 105 a frame; a transversely disposed cylinder carried by said frame; a piston in said cylinder; a piston rod rigid with said piston, provided with a series of teeth; a member slidable transversely of the axis of said piston rod, adapted to engage said teeth to prevent movement of said rod, means operable in one direction by fluid pressure for sliding said member out of engagement with said teeth; and a pile engaging rail carried by 110 said piston rod.

16. In a trench wall supporting machine, 120 a frame; a transversely disposed cylinder carried by said frame; a piston in said cylinder; a piston rod rigid with said piston, provided with a series of teeth; a member slidable transversely of the axis of said piston rod, adapted to engage said teeth to prevent movement of said rod; an auxiliary cylinder; a piston in said auxiliary cylinder; connections between said last named piston and said slidable member for moving the latter; and a pile engaging rail carried by 125 said piston rod.

17. In a trench wall supporting machine,

a frame; a transversely disposed cylinder carried by said frame; a piston in said cylinder; a piston rod rigid with said pistons, provided with a series of ratchet teeth; a 5 slide dog adapted to engage said teeth to prevent movement of said rod in one direction; an auxiliary cylinder; a piston in

said auxiliary cylinder, movable in one direction by fluid pressure, a spring for moving said last named piston in the other direction; a rock lever connecting said last named piston and dog; and a pile engaging rail carried by said piston rod.

SYDNEY BURT GARDNER.
